Des. 220,386
Patented Apr. 6, 1971

220,386

COMBINED TRAVEL TRAILER AND BOAT

Frank S. Kovach, South Bend, Ind., assignor to Buccaneer
Travel Trailer Corporation, Osceola, Ind.

Filed Dec. 24, 1969, Ser. No. 20,636

Term of patent 3½ years

Int. Cl. D12—10

U.S. Cl. D14—3

Fig. 1

Fig. 2

Fig. 3

Fig. 4

FIG. 1 is a perspective view of a combined travel trailer and boat having my new design.

FIG. 2 is a side elevation of the combined travel trailer and boat design of FIG. 1.

FIG. 3 is a front elevation of the combined travel trailer and boat design of FIG. 1.

FIG. 4 is an end elevation of the combined travel trailer and boat design shown in FIG. 1.

I claim:

The ornamental design for a combined travel trailer and boat, as shown.
